Primary Examiner — Cathron C Brooks*Assistant Examiner* — Kevin K Rudzinski(74) *Attorney, Agent, or Firm* — Park, Kim & Suh, LLC(57) **CLAIM**

The ornamental design for a lens for an LED lamp, as shown and described.

DESCRIPTION

FIG. 1 is a perspective view of a lens for an LED lamp showing my new design;

FIG. 2 is a front view thereof, a rear view being a mirror image of the front view;

FIG. 3 is a left side view thereof, a right side view being a mirror image of the left side view;

FIG. 4 is a top plan view thereof;

FIG. 5 is a bottom plan view thereof;

FIG. 6 is a cross-sectional view taken along line 6—6 in FIG. 4;

FIG. 7 is a cross-sectional perspective view taken along line 6—6 in FIG. 4; and,

FIG. 8 is a perspective view showing the lens in an environment of use with an LED lamp.

The broken lines shown in the figures illustrate environmental structures and form no part of the claimed design.
